INVENTOR

UNITED STATES PATENT OFFICE.

ALBERT F. NATHAN, OF PLAINFIELD, NEW JERSEY.

DIAPHRAGM.

1,413,234.

Specification of Letters Patent. Patented Apr. 18, 1922.

Application filed April 29, 1920. Serial No. 377,634.

To all whom it may concern:

Be it known that I, ALBERT F. NATHAN, a citizen of the United States, and residing at No. 530 Woodland Avenue, Plainfield, in 5 the county of Union and State of New Jersey, have invented an Improved Diaphragm, of which the following specification is a full disclosure.

This invention deals with an improved 10 diaphragm for the sound box of a phonograph, and it consists of two external plates of vitreous material, such as glass, intimately adhering to an intervening sheet of a dissimilar material such as celluloid.

15 It has heretofore been proposed to use a simple plate or sheet of glass as a diaphragm, on account of the well-known acoustical properties of this material but great difficulty has been experienced in a practical 20 sense, owing to the fragile nature of glass. Other substances, such as mica, wood, parchment, and the like, have therefore been proposed and extensively used; a chief advantage residing in their non-fragile character.

25 It is difficult to obtain mica of a perfectly uniform nature on account of its common imperfections, and the other enumerated materials are hydroscopic in character and therefore vary from day to day in point of 30 stiffness and degree of resiliency.

Glass admits of being cemented to celluloid so intimately that it is impossible thereafter to separate them without destroying the celluloid. This union can be effected by the 35 application of heat and pressure, and by using a suitable cementitious or unifying ingredient. By reason of the heat and pressure required, the union can best be effected by employing comparatively thick pieces of 40 glass, and it is possible to form a "sandwich," of which the three members are virtually in a state of molecular adhesion and incapable of subsequent separation even when the glass is broken and greatly fractured. 45 It is feasible to use a sheet of celluloid ranging in thickness from, say, twenty thousandths of an inch down to around seven thousandths of an inch, and to effect the union under such conditions that the 50 ultimate intervening layer of celluloid will not be more than five thousandths of an inch in thickness and perhaps somewhat less.

This invention contemplates various rela-

tions in the thickness of the three elements. This will appear upon reference to the accompanying drawings, of which:—

Fig. 1 is a side elevation of a tone arm embodying this diaphragm.

Figs. 2, 3 and 4 are cross sections of modified diaphragms, and Fig. 5 is a section 60 through a sound box exemplifying the installation of the diaphragm.

Fig. 2 shows an intermediate strip of celluloid, exteriorly faced with two layers of glass *a* and *c*. In this instance, the thickness of the respective elements is so graduated that the glass films are substantially one half the thickness of the celluloid. In the form shown by Fig. 3, the glass facings *a'* and *c'* are of substantially the same thickness as the intervening sheet *b* of celluloid, whereas in Fig. 4 the plates of glass *a''* and *c''* are each fifty per cent thicker than the enclosed sheet of celluloid *b*.

These diaphragms may be made by starting with glass and celluloid of appropriate sizes and cementing them together to produce the ultimate article, but in case it is desired that the glass facings should be made quite thin, very perfect results can be 80 obtained by making the diaphragm initially of plates of glass sufficiently thick to withstand any necessary pressure used in the formative process, and thereafter grinding down the glass plates until their thicknesses 85 have been reduced to the required amount. It is not necessary to follow the grinding operation with a polishing step, although this can be done if desired, inasmuch as a very good acoustical result may be obtained 90 by using ground glass. A handsomer appearance can, however, be obtained by polishing the glass, and the cost is not prohibitive, owing to the fact that this grinding and polishing work is done almost entirely 95 by machinery.

After the diaphragms have been finished, their edges may be bevelled as indicated in the drawings, and then they are centrally apertured and mounted. For example, as 100 shown by Figs. 1 and 5, the diaphragm *A* is centrally apertured to receive a screw 6, which binds it to the extremity 5 of a vibrator 4, which is actuated by the holder 3, which carries a thumb screw 2 for retaining 105 a stylus 1. A little suitable wax or rose-

metal solder 7 will prevent the screw 6 from shaking loose. The diaphragm may be mounted in a conventional manner, as by placing it between two resilient rings B, 5 held in place by an annulus D against a holder C, which constitutes a part of the sound box carried by the sound tube E, which, in a Victor machine, is pivoted at F to a tone arm proper G.

10 It will be perceived that this diaphragm is non-hydroscopic and, not easily broken, being constructed of reinforced glass. It furthermore possesses a very high degree of resiliency, owing to the permanent adhesion 15 of its elements, and owing to the fact that the least resilient element, to-wit, the celluloid, occupies the neutral zone whereas the active flexing regions are occupied by glass which, as is well known, is noted for its lack 20 of elastic limit, i. e., its inability to take any permanent set under tension or compression. This diaphragm, therefore, not only uses materials of an entirely suitable nature and possessing proper characteristics 25 for the purpose in hand, but these materials are disposed and united also in the manner best suitable for that purpose.

I therefore claim as my invention:—

1. A diaphragm for recording or reproducing instruments composed of an intermediate sheet externally faced with glass intimately bonded thereto; the total thickness being such as easily to permit of flexure. 30

2. A flexural diaphragm consisting of an intermediate film of celluloid and two films of glass externally applied thereto so as to be in a state of intimate adhesion to said celluloid. 35

3. A flexural diaphragm consisting of two thin plates of ground glass and an intermediate layer of celluloid intimately bonded to said glass at all points of contact. 40

4. A sound box combining a flexural diaphragm consisting of celluloid externally faced with glass, and a stylus secured centrally to said diaphragm. 45

In witness whereof, I hereunto subscribe my name, as attested by the two subscribing witnesses.

ALBERT F. NATHAN.
